UNITED STATES PATENT OFFICE.

LORENZ L. MEYER, OF WENTWORTH, SOUTH DAKOTA.

MANURE LOADER.

Application filed August 26, 1921. Serial No. 495,623.

To all whom it may concern:

Be it known that LORENZ L. MEYER, a citizen of the United States of America, residing at Wentworth, in the county of Lake and State of South Dakota, has invented new and useful Improvements in Manure Loaders, of which the following is a specification.

The object of the invention is to provide a machine adapted for loading manure and similar material from the ground or pile into a suitable vehicle or receptacle but especially designed as the means of removing manure from a bed which has accumulated on the floor of the stable as a means of avoiding the necessity of forking or otherwise manually handling or removing the same, the apparatus being designed to operate progressively as the material is loosened and conveyed to a point of deposit which may as indicated consists of a suitable vehicle; and with this object in view the invention consists in a construction and combination of parts of which a preferred embodiment is shown in the accompanying drawings, wherein:—

Figure 1 is a side view of an apparatus embodying the invention.

Figure 2 is a plan view of the same.

Figure 3 is a longitudinal sectional view.

Figure 4 is a front view.

Figure 5 is a transverse section on the plane indicated by the line 5—5 of Figure 2.

The frame 10 which may be of any suitable or preferred construction is wheel supported as by the rear wheels 11 and the front wheels 12 carried by a pivotal axle 13 to provide for the forward movement of the machine through suitable draft gear including for example the tongue 14, and carried by the frame is a conveyor 15 having a front elevator portion 16 and a rear shoe portion 17 of which the inlet end is adapted to rest on the floor or surface in position to have the manure or like material conveyed thereto with facility as by means of a fork 18. It is preferred to operate the conveyor with its elevating and foot extensions by means of a motor 19 of any suitable type serving to operate the main drive shaft 20 and through suitable connections with the other parts of the mechanism as by belts and pulleys or chains and sprockets as indicated and a detailed description of which is deemed unnecessary in

view of the fact that modification thereof may be made without in any way departing from the principles involved. When the machine is arranged for operation in removing and conveying the manure for discharge by the upper end of the elevator member into a suitable receptacle or vehicle the elevator member 16 should be supported at the desired inclination as by means of a brace rod 21 and the front axle should be locked against pivotal or swinging movement by means of a brace 22, while the feed or shoe end of the conveyor should be adjusted vertically by means of the thumb nut 23 engaging a bolt 24 operating in a slot 25 in the adjacent portion of the frame.

Also in the operation of the mechanism it is proposed to advance or cause progressive movement of the same in the rearward direction so that the feed end of the shoe member of the conveyor may advance as the manure is transferred from the pile or floor to the conveyor by the fork 18, and to this end there is employed a pivotal draft loop 26 with which is connected a draft cable 27 adapted to extend around a suitable guide pulley 28 secured to a wall or partition or post in the stable and reeled upon a drum 29 which may be connected for operation with the drive shaft by means of a suitable clutch 30 or the equivalent thereof. The crossbar 31 of the draft loop is preferably provided with a series of seats 32 with any of which the end of the draft cable may be engaged to provide for varying the direction of progress of the machine without varying the position of the guide pulley.

Operatively connected with the drive shaft is a crank shaft 33 having a crank 34 upon which is mounted the inner end of the staff 35 of the fork, said staff extending slidably through the guide sleeve 36 supported by a hanger rod 37, the upper extremity of which is loosely connected with the wrist pin 37^a of a crank 37^b forming one extremity of a shaft 37^c rotatably mounted in a bracket 38 which is pivotally supported, as at 38^a. The shaft 37^c is rotated by means of operative connections between it and the crank shaft 33 and the crank 37^b, thus raising and lowering the hanger rod 37 which imparts up and down movement to the fork while the crank 34 imparts forward and rear movement to the same. The fork is thus caused to traverse an orbital path which will enable it upon

its inward stroke to pass over the feed end of the shoe of the conveyor and relatively close to the same without contact therewith, the fork at the same time being elevated during its outward stroke in order to pass over and then come down into engagement with the manure or material to be moved, being then drawn inward into a depressed position so as to gather the manure 10 and transfer it to the shoe for conveyance by the latter and the cooperating portions of the conveyor and elevator to the point of discharge at the remote end of the elevator. The positioning of the bracket 38 to 15 vary the orbital path of the fork is controlled by a hand lever 39 having a suitable locking pawl traversing a toothed segment 40 whereby it may be locked in adjusted position.

20 It is obvious that the machine may be moved progressively as the material is gathered either from a pile or an accumulation on the floor of the stable to keep the fork always within reach of the material to be 25 moved. In order that the position of the fork laterally with relation to the feed end of the shoe may be varied, the shaft 37 is employed by means of a worm and gear connection 41 to impart rotary movement 30 to a shaft 42, the latter having a bevel gear connection 43 with a transverse shaft 44 which is operatively connected with the shaft 45 of which the upper end is rotatably mounted in a bearing sleeve 46. The 35 shaft 45 is provided with a crank arm 47 and a link 48 connects the extremity of the crank arm with the guide sleeve 36. Thus, the rotation of the shaft 45 imparts movement to the sleeve 36 transversely of the 40 machine and causes a corresponding trans-

verse back and forward movement of the fork.

Having described the invention, what is claimed as new and useful is:—

1. A manure loading apparatus having a 45 wheel supported frame, a conveyor having terminal shoe and elevator portions, a fork arranged in operative relation with the feed end of the shoe for drawing material into position upon the shoe, and means for operating said fork including a crank with which the staff of the fork is connected, a guide sleeve for the staff, and means for varying the position of said sleeve.

2. A manure loading apparatus having a 55 wheel supported frame, a conveyor having terminal shoe and elevator portions, a fork arranged in operative relation with the feed end of the shoe for drawing material into position upon the shoe, and means for operating said fork including a crank shaft with which the staff of the fork is connected, a guide sleeve through which the staff slides, and means for moving the sleeve transversely with relation to the conveyor.

3. A manure loading apparatus having a 60 wheel supported frame, a conveyor having terminal shoe and elevator portions, a fork arranged in operative relation with the feed end of the shoe for drawing material into 65 position upon the shoe, and means for operating said fork and including a crank shaft with which the staff of the fork is connected, a guide sleeve in which the staff is slidably mounted, and means including a crank shaft for imparting transverse movement to 70 said guide sleeve.

In testimony whereof he affixes his signature.

LORENZ L. MEYER.
